Inventor:

David Bourque

Henry Scott, Jimmy + Jimmy
Ellery

UNITED STATES PATENT OFFICE.

DAVID BOURQUE, OF AMESBURY, MASSACHUSETTS, ASSIGNOR TO G. W. J. MURPHY COMPANY, OF AMESBURY, MASSACHUSETTS, A CORPORATION OF MASSACHUSETTS.

FASTENER FOR AUTOMOBILE HOODS AND THE LIKE.

Application filed December 13, 1919. Serial No. 344,541.

To all whom it may concern:

Be it known that I, DAVID BOURQUE, a citizen of the United States, and a resident of Amesbury, county of Essex, State of Massachusetts, have invented an Improvement in Fasteners for Automobile Hoods and the like, of which the following description, in connection with the accompanying drawings, is a specification, like characters on the drawings representing like parts.

This invention relates to fastening devices for securing in position the hinged leaves or flaps which form a part of the hoods or bonnets of motor cars.

My invention will best be understood by reference to the following description taken in connection with the accompanying drawings showing a hood fastener for automobiles embodying my invention and wherein:

Fig. 1 is a side elevation of the hood or bonnet of a motor car;

Fig. 2 is a view on an enlarged scale from the same point of observation, showing the fastening device in end elevation;

Fig. 3 is a side elevation thereof; and

Fig. 4 is a view similar to Fig. 3 showing the parts in a different position.

In the drawings I have shown in Fig. 1 the usual hood of a motor vehicle embodying on either side hinged leaves or flaps 5 and 7 extending between the cowl 9 and the radiator 11, adapted to be folded down to the position shown and closing inwardly against suitable supports 13 on the frame as shown at the broken away portion of Fig. 1.

My invention provides suitable latching means for holding the leaf 7 pressed inwardly against the supports 13. Referring to Figs. 3 and 4, I herein provide the flap 7 with a suitable engaging surface to cooperate with the latching member and this may take the form of a socket 15 adapted to be riveted to the flap 7 and provided with a recess to receive a plug 17 of suitable noise-deadening material which is preferably presented diagonally, as shown, so that pressure axial of the plug will press the leaf 7 inwardly against the supports 13 and also downwardly.

In the form of the invention chosen for purposes of illustration the frame provides along either side a ledge 19 paralleling the edge of the closed leaf 7 and this ledge may be utilized for supporting the latching mem-

bers, which members I shall next describe. The latching members comprise a pivoted latch proper supported in any suitable way but herein where the ledge 19 is provided a suitable plate 21 may be attached to this ledge, the plate having a pair of ears 23 receiving the pivot pin 25 and with which cooperate ears 27 on the latch member proper. This latch member is herein shown as having a hollow body portion 29, the sides of which are extended to form the ears 27, a projecting bill 31 sloping inwardly and downwardly and a handle portion 33 herein in the nature of a terminal hook. The latch member is adapted to fold directly in against the abutment surface provided on the member 15, the bill 31 engaging the plug 17 and preferably, as shown, with a mere face to face engagement without interlocking therewith. The latch in its inward position presses axially on the diagonally presented engaging surface of the hood and consequently presses the leaf 7 both inwardly against the supports 13 and downwardly and is thus adapted to hold the hood securely and without opportunity for any lost motion.

To hold the latch member in its engaging position a spring may be provided and I have herein shown a spiral spring 35 partially housed in the hollow body of the latch and secured thereto and to a relatively fixed point, herein a hook 37 located on the base plate 21 between the ears 23. The connecting points of the spring are so arranged with respect to the pivot 25 that the spring swings past this pivot as illustrated by Figs. 3 and 4 and is thus adapted to hold the latch on either side of dead center, either in the position shown in Fig. 3 in which the force of the spring is exerted to press the bill 31 against plug 17 or in the position shown in Fig. 4 in which it is exerted to hold the latch in its open position, the ears 27 being provided with portions of greater radius which come in contact with the shoulders 39 of ears 23 to limit the opening movement of the latch in a clockwise direction, viewing Figs. 3 and 4.

It will be seen that the construction herein provided is exceedingly neat and simple and is adapted to exert a strong inward and downward pressure against the flap of the hood holding it tightly against its inward supports and preventing it from rattling

- under the vibration of the car. The device is easily operated to throw the latch from one side of dead center to the other even although the spring is very strong and 5 there is no necessity of compressing a spring unduly in order to engage the fastening as in the case of many hooked devices wherein the spring has to be strained beyond actual working tension in order to engage the 10 parts. When the device is opened it is securely held and locked open while the leaves or flaps of the hood are being lifted and there are no loose parts to shake or strike against adjacent objects.
- 15 Having thus described one specific embodiment of my invention, the principles exemplified thereby which I claim as new and desire to secure by Letters Patent I shall express in the following claims:
- 20 1. In a motor vehicle a hood having a depending flap provided with an interior support, upwardly presented diagonal abutments adjacent the lower edge of the flap and means for pressing the flap downwardly 25 and inwardly on its support comprising pivoted latches mounted exteriorly of the hood and having bill portions adapted to close downwardly on said abutments and springs tending to swing the latches about
- their pivots for holding said latches with the bills in engagement with the abutments. 2. In a motor vehicle a hood having a depending flap provided with an interior support, upwardly presented diagonal abutments adjacent the lower edge of the flap 35 and means for pressing the flap downwardly and inwardly on its support comprising pivoted latches mounted exteriorly of the hood and having bill portions adapted to close downwardly on said abutments and 40 springs for holding said latches on either side of dead center and in one such position with the bills in engagement with the abutments.
3. In a motor vehicle having a depending hood flap provided with an interior support, latches pivoted to the vehicle frame adjacent the lower edge of the flap and exteriorly thereof and springs for holding said latches on either side of dead center, 50 said latches having bills to engage the flap and upwardly extending terminal portions providing an unobstructed handle to be encircled by the fingers whereby the latches may be rocked past dead center. 55

In testimony whereof, I have signed my name to this specification.

DAVID BOURQUE.
